ROOF INSULATION VENTILATOR

Robert W. Mason, Port Credit, Ontario, Canada, assignor to Marathon Equipment & Supply Limited, Weston,
Ontario, Canada

Filed Aug. 21, 1970, Ser. No. 24,632

Term of patent 14 years

Int. Cl. D23—04; D29—02
U.S. Cl. D23—153

FIG. 1 is a top perspective view of a roof insulation ventilator showing my new design;

FIG. 2 is a bottom perspective view thereof; and

FIG. 3 is a side elevational view thereof.

I claim:

The ornamental design for a roof insulation ventilator,
as shown and described.
